UNITED STATES PATENT OFFICE.

JOHN CONNOLLY, OF BOSTON, MASSACHUSETTS.

IMPROVED CASK.

Specification forming part of Letters Patent No. 39,274, dated July 21, 1863.

To all whom it may concern:

Be it known that I, JOHN CONNOLLY, of Boston, in the county of Suffolk and State of Massachusetts, have invented a new and useful Improvement in the Construction of Casks; and I do hereby declare that the following is a full, clear, and exact description of the same, reference being had to the accompanying drawings, making a part of this specification, in which—

Figure 1 is a side sectional view of a cask constructed according to my invention; Fig. 2, a plan or top view of the same.

Similar letters of reference indicate corresponding parts in the two figures.

This invention relates to a new and useful improvement in the construction of casks, barrels, kegs, &c., and is applicable to either metal or wooden articles above named.

The invention consists in the employment or use of a metal head, provided with an internal screw, which works on a male screw on the cask, barrel, or keg, and constructed and arranged as hereinafter fully shown and described, whereby it is believed that many advantages are obtained over casks, barrels, &c., constructed in the ordinary manner.

To enable those skilled in the art to fully understand and construct my invention, I will proceed to describe it.

A represents the body or main portion of a wooden barrel, *a* being the staves, and *b* the hoops. These parts are of ordinary construction, and therefore do not require a minute description.

B represents the metal heads of the barrel. These heads may be of any suitable thickness, and they are swaged or otherwise formed, so as to have an elevated rim, *c*, which serves as a cap for the ends of the staves, and also to have a flange, *d*, to project down over the outer sides of the staves. This flange *d* has a screw, *e*, cut on its inner side, so that the flange may be screwed on or over the end of the barrel, as shown clearly in Fig. 1. The head proper—that is to say, the portion within the cap or rim *c*—is considerably sunken, so as to admit of a requisite projection of the rim corresponding to the chine of an ordinary barrel. The head is provided with two teats or pins, *f*, to receive a lever or wrench, by which the flange *d* is screwed on the barrel. The ordinary wooden barrel, as is well

known, is provided with wooden heads bevelled at their periphery and fitted in a croze made in the inner sides of the staves at a short distance from their ends, the staves being bound snugly together and around the head by hoops. The principal disadvantages attending this mode of construction are as follows: The croze weakens the staves and the chines of the barrel are very liable to be broken off by the rough usage they receive, and when broken cannot be repaired so as to be reliable or durable. The fibers of the wood also, between the head and the hoop, are frequently compressed to such a degree by the driving of the hoop as to lose their resistance to strain, and the slightest stroke or blow will in this case frequently break the chine. The wooden heads also are liable to shrink and in that case lose their perfect circular form, which renders a tight joint around the head almost impossible. These difficulties are fully obviated by my invention, and in case the barrel shrinks the head may be screwed farther on the barrel, so as to bring the staves compactly together and form perfectly-tight joints between them. In order to carry out this plan fully I design to have the flanges *d* only partly screwed down at first to form perfect joints, thus leaving room in the cap or rim *a* for a further screwing down, if shrinkage renders it necessary. I will remark, however, that in the event of shrinkage after the head is screwed fully down the latter may be removed, the ends of the staves sawed off, and the head again applied to the barrel. The screw *e* will form its own thread on the barrel.

It will be seen by referring to Fig. 1 that the bilge of the barrel, in connection with an inclination which is given the flange *d*, insures the staves being pressed inward as the head is screwed on the barrel.

The invention may be applied to metal casks, the latter being formed or rolled out of a solid plate or made in sections and fitted together with any suitable form of joint.

My invention not only insures a perfect and durable cask, but it also greatly reduces the cost of construction, as the usual work of chamfering, howeling, crozing, and fitting the head is avoided, and the head serves as a hoop and a cap for the ends of the staves, all combined in one piece.

Having thus described my invention, what

I claim as new, and desire to secure by Letters-Patent, is—

A metallic head for casks, barrels, kegs, &c., formed with an elevated rim or cap, *a*, and a flange, *d*, provided with a screw, *e*, on its inner surface, and all constructed and arranged as shown, so as to be capable of being

applied in the manner substantially as set forth.

JOHN CONNOLLY.
